UNITED STATES PATENT OFFICE.

PHILIP C. HOLDEN, OF CONCORD, MASSACHUSETTS, ASSIGNOR TO UNITED DRUG COMPANY, OF BOSTON, MASSACHUSETTS, A CORPORATION OF MASSACHUSETTS.

DESIGN FOR A FONT OF TYPE.

47,594.

Specification for Design.

Patented July 20, 1915.

Application filed May 22, 1915. Serial No. 29,918. Term of patent 14 years.

To all whom it may concern:

Be it known that I, PHILIP C. HOLDEN, a citizen of the United States, residing at No. 12 Hubbard street, town of Concord, county of Middlesex, and Commonwealth of Massachusetts, have invented a new, original, and ornamental Design for a Font of Type, of which the following is a specification, reference being had to the accompanying drawing, forming part thereof.

The figure is a plan view of a font of type, showing my new design.

I claim:

The ornamental design for a font of type, as shown.

Dated May 20th, 1915.

PHILIP C. HOLDEN.

Witnesses:

ROBERT J. EGLES,
MARCUS E. MAHON.
